UNITED STATES PATENT OFFICE.

ASA F. BATCHELDER, OF SCHENECTADY, NEW YORK, ASSIGNOR TO GENERAL ELECTRIC COMPANY, A CORPORATION OF NEW YORK.

ELECTRIC LOCOMOTIVE.

1,189,341.

Specification of Letters Patent. Application filed March 16, 1916. Serial No. 84,724.

Patented July 4, 1916.

To all whom it may concern:

Be it known that I, ASA F. BATCHELDER, a citizen of the United States, residing at Schenectady, in the county of Schenectady, State of New York, have invented certain new and useful Improvements in Electric Locomotives, of which the following is a specification.

My invention relates to electric locomotives and particularly to the construction and arrangement of the cabs of such locomotives.

The main object of my invention is a novel construction and arrangement of such cabs in which portions of the controlling apparatus including the resistance sections and the contactors, are housed in a central compartment of the cab with passage-ways about the compartment, the resistance sections being located in the bottom of the compartment and the contactors above the resistance sections. With this arrangement of these portions of the controlling apparatus all danger of the operators of the locomotive coming in contact therewith in passing through the cab of the locomotive is removed. By providing doors in the side-walls of the compartment, access may be had to the resistance sections and the contactors so that they may be conveniently inspected and removed from within the cab, and by providing a passage way in the compartment between the contactors they may also be inspected from this passage way. Furthermore, my arrangement of this portion of the controlling apparatus permits the resistance sections thereof to be efficiently cooled by natural ventilation as will be hereinafter pointed out.

The various features of novelty which characterize my invention are pointed out with particularity in the claims annexed to and forming a part of this specification. For a better understanding of my invention reference may be had to the following description taken in connection with the accompanying drawings in which—

Figure 1 is a longitudinal elevation, with parts removed, of a locomotive embodying my invention; Fig. 2 is a section on the line 2—2 of Fig. 1, and Fig. 3 is a section on the line 3—3 of Fig. 1.

Referring to the drawing, 4, 4 are trucks on which the locomotive cab is mounted in

any well known and usual manner. The cab 55 has a floor 5, side-walls 6, end walls 7 provided with doors 8, and a roof 9. In the cab is a central compartment which has side-walls 10 parallel with but spaced from the side-walls 6 of the cab so as to form passage-ways 11 between the compartment and the side-walls of the cab. This compartment contains resistance sections 12 and contactors 13 of the controlling apparatus. The resistance sections 12 are located in the bottom of the compartment and the contactors 13 are located in the compartment above the resistance sections and are separated therefrom by a partition 14. The contactors are preferably placed in rows on both sides of 70 the compartment with a passage way 15 between them, the arc chutes 16 of those on one side facing the arc chutes 16 of those on the other side. Doors 17 and 18 are provided in the side-walls of the compartment. 75 The doors 17 give the operators access to the connections of the contactors 13 from the passage-ways 11 and the doors 18 give the operators access to the resistance sections 12 from these same passage-ways. The 80 doors 17 and 18 are made so that they may be entirely removed and may therefore be taken to a remote part of the locomotive when it is necessary to do any work on the contactors or resistance sections. By placing 85 the contactors 13 with the arc chutes of those on one side facing the arc chutes of those on the other with a passage-way between them, a large arcing space is provided in front of the contactors and by providing openings at 90 the ends of the compartment to the passage-way 15, access is given to the contactors for their inspection and repair. Doors 19 may be provided at the ends of the passage-way 15. 95

It will be noted from Fig. 3 of the drawing that the portion of the roof of the cab over the passage-ways 11 is lower than the portion of the roof over the central compartment, windows 20 being provided 100 in the side-walls of the compartment, above the portion of the roof over the passage-ways and windows 21 in the side-walls of the cab adjacent to the passage-ways 11. The windows 20 permit light to enter the 105 central compartment so that the operators may, during the day time, work in the central compartment without artificial light

and the windows 21 in the side-walls of the cab permit the operators to work on the rheostat sections 12 and the connections of the contactors 13 in the same way.

- 5 Ventilating flues 23 are connected to the bottom portion of the central compartment and extend upwardly through the roof of the cab. The floor of the cab beneath the resistance sections has openings 24 therein 10 through which air from the outside of the locomotive is drawn by convection to cool the resistance sections, the heated air passing out through the ventilating flues 23. By placing the resistance sections in the 15 bottom of the compartment and extending the ventilating flues 23 upward through the roof of the locomotive it is possible to make this flue of considerable length and consequently there will be a good, natural draft 20 of ventilating air over the resistance sections.

The locomotive, illustrated in the drawings, has at one end a motorman's compartment separated from the rest of the cab 25 by a wall 25 and doors 26. This compartment contains the master controller 27 and the air brake motorman's valves 28. There is also shown in this compartment a heater 29 for heating the motorman's compartment. Between the motorman's compartment and the central compartment of the cab is an inclosed space which contains a water tank 30 on which is mounted a motor generator 31, this motor generator set is 30 used in the control system of the locomotive and drives a fan 32 for ventilating the motors of the locomotive. The fan 32 draws air from outside the locomotive through louvres 33 in the side-walls 6 of the cab. 35 This portion of the cab also contains parts of the controlling apparatus, such as a motor operated controller 35 and switches 36. At the other end of the locomotive there is an uninclosed space which contains a 40 steam boiler 37 and a fuel tank 38 therefor. The steam boiler 37 obtains water from the water tank 30, and supplies steam for heating the train. In this portion of the locomotive is also located air compressors 39 for 45 supplying compressed air to the air brake system and a high tension switch compartment 40 together with a lightning arrester or reactor 41. Fastened on the ends of the central compartment are sand boxes 42. It 50 will be noted that these sand boxes are adjacent the ventilating flues 23, the sand therein being thus kept dry without extra heating apparatus.

I desire it to be understood that my invention is not limited to the particular arrangement herein shown and described, and I aim in the appended claims to cover all modifications which do not depart from the spirit and scope of my invention.

65 What I claim as new and desire to se-

cure by Letters Patent of the United States, is:—

1. In an electric locomotive, the combination with controlling apparatus therefor comprising resistance sections and contactors, of a cab having a floor, side-walls, and a roof, a central compartment having side-walls parallel with but spaced from the side-walls of the cab and thereby forming passage-ways between said compartment 70 and the side-walls of the cab, said resistance sections being located in the bottom of said compartment, said contactors being located in said compartment above said resistance sections and separated therefrom 80 by a partition.

2. In an electric locomotive, the combination with controlling apparatus therefor comprising resistance sections and contactors, of a cab having a floor, side-walls, and a roof, a central compartment having side-walls parallel with but spaced from the side-walls of the cab and thereby forming passage-ways between said compartment 85 and the side-walls of the cab, said resistance sections being located in the bottom of said compartment, said contactors being located in said compartment above said resistance sections and separated therefrom by a partition, said contactors being placed in rows 90 on both sides of said compartment with a passage-way between them, the arc chutes of those on one side facing the arc chutes of those on the other side.

3. In an electric locomotive, the combination with controlling apparatus therefor comprising resistance sections and contactors, of a cab having a floor, side-walls, and a roof, a central compartment having side-walls parallel with but spaced from the side-walls of the cab and thereby forming 100 passageways between said compartment and the side-walls of the cab, said resistance sections being located in the bottom of said compartment, said contactors being located in said compartment above said resistance sections and separated therefrom by a partition, said contactors being placed in rows 105 on both sides of said compartment with a passage-way between them, the arc chutes of those on one side facing the arc chutes of those on the other side, and doors in the side walls of 110 said compartment for giving access to said resistance sections and to the connections of said contactors.

4. In an electric locomotive, the combination with controlling apparatus therefor, of a cab having a floor, side-walls, and a roof, a central compartment for containing parts of said controlling apparatus having side-walls parallel with but spaced from the side-walls of the cab, and thereby forming 115 passage-ways between said compartments and the side-walls of the cab and doors in the side-walls of said compartment for giving 120

125

130

- access to said controlling apparatus from said passage-ways, the portion of said roof of said cab over said passage-ways being lower than the portion of said roof over 5 said central compartment, windows in the side-walls of said compartment and above the portion of the roof over said passage-ways, and windows in the side-walls of said cab adjacent said passage-ways.
- 10 5. In an electric locomotive, the combination with controlling apparatus therefor comprising resistance sections and contactors, of a cab having a floor, side-walls, and a roof, a central compartment having side-walls parallel with but spaced from the side-walls of the cab and thereby forming passage-ways between said compartment and the side-walls of the cab, said resistance sections being located in the bottom of said 15 compartment, said contactors being located in said compartment above said resistance sections and separated therefrom by a partition, ventilating flues connected to the portion of said compartment containing the resistance sections and extending upwardly through the roof of said cab, the floor of the cab beneath the resistance sections being provided with openings whereby cooling air circulates over said resistance sections and 20 out through said ventilating flues.
6. In an electric locomotive, the combination with controlling apparatus therefor comprising resistance sections and contactors, of a cab having a floor, side-walls, and a roof, a central compartment having side-walls parallel with but spaced from the side-walls of the cab and thereby forming passage-ways between said compartment and the side-walls of the cab, said resistance sections being located in the bottom of said 25 compartment, said contactors being located in said compartment above said resistance sections and separated therefrom by a partition, said contactors being placed in rows 30 on both sides of said compartment with a passage-way between them, the arc chutes of those on one side facing the arc chutes of those on the other side, doors in the side-walls of said compartment for giving access 35 to said resistance sections and to the connections of said contactors, and ventilating flues connecting to the portion of said compartment containing the resistance sections and extending upwardly through the roof of 40 said cab, the floor of said cab beneath the resistance sections being provided with openings whereby cooling air circulates over said resistance sections and out through said 45 ventilating flues.
7. In an electric locomotive, the combination with controlling apparatus therefor comprising resistance sections and contactors, of a cab having a floor, side-walls, and a roof, a central compartment having side-walls parallel with but spaced from the side-walls of the cab and thereby forming passage-ways between said compartment and the side-walls of the cab, said resistance sections being located in the bottom of said 50 compartment, said contactors being located in said compartment above said resistance sections and separated therefrom by a partition, said contactors being placed in rows 55 on both sides of said compartment with a passage-way between them, the arc chutes of those on one side facing the arc chutes of those on the other side, doors in the side-walls of said compartment for giving access 60 to said resistance sections and to the connections of said contactors, and ventilating flues connecting to the portion of said compartment containing the resistance sections and extending upwardly through the roof of 65 said cab, the floor of said cab beneath the resistance sections being provided with openings whereby cooling air circulates over said resistance sections and out through said 70 ventilating flues.

In witness whereof, I have hereunto set my hand this 15th day of March, 1916.
ASA F. BATCHELDER.
